Primary Examiner — Lilyana Bekic*(74) Attorney, Agent, or Firm* — King & Schickli, PLLC(57) **CLAIM**

The ornamental design for a respiratory mask, as shown and described.

DESCRIPTION

FIG. 1 is a front and right side perspective view of a respiratory mask showing our new design;

FIG. 2 is a front view thereof;

FIG. 3 is a rear view thereof;

FIG. 4 is a top view thereof;

FIG. 5 is a bottom view thereof;

FIG. 6 is a right side view thereof; and,

FIG. 7 is a left side view thereof.

The broken lines in the drawings depict portions of the respiratory mask that form no part of the claimed design.

1 Claim, 7 Drawing Sheets(56)
